Louis George Copes
INVENTOR

UNITED STATES PATENT OFFICE

LOUIS GEORGE COPIES, OF BAYONNE, NEW JERSEY

MULLER

Application filed October 20, 1926. Serial No. 142,994.

In such operations as the rubbing or grinding of pigments with oil or other vehicle by means of the conventional form of muller or by means of a spatula or palette knife, it is found that the process is wasteful of time and yields a finished product that is lacking in uniformity of subdivision of the pigment particles regardless of the industry and perseverance of the operator. By one or the other of these well known and universally used methods it is practically impossible even after protracted manipulation of the muller or spatula, to produce a mixture in which some particles of pigment have not escaped completely the grinding action of the appliance, or at least in which part of the pigment is much less thoroughly ground than the remainder.

The invention relates to an improved form of muller which is applicable to the grinding of pigments or similar pulverulent materials with oil or other vehicle, simulating in principle and effect the action of the conventional paint mill upon mixtures of the type used in manufacturing paints, and when properly manipulated yielding a product of which none of the solid portion (pigment) can escape the desired thorough and uniform grinding action of the appliance, and this too in a relatively brief time and with a minimum of labor.

One convenient form of the invention is illustrated in the accompanying drawings, wherein

Figure 1 is an inverted or bottom plan view of a muller embodying my invention.

Figure 2 is a vertical sectional view thereof.

Figure 3 is a vertical section similar to Figure 2 illustrating the grinding action of the muller upon material lodging on a plane surface.

The muller consists essentially of a hollow, tubular unit, preferably cylindrical, of steel, glass, porcelain, or other suitable material, of a size convenient to fit the hand. The under surface of the muller constitutes the grinding surface. Such grinding surface may be a smooth plane surface, as at A, Figure 1, but preferably the grinding surface may be, and is, indented at B, such indenta-

tions being in the form of channels arranged in comparatively close order as shown in the upper left-hand portion of Figure 1. These channels are shown as tangential to the cylindrical surfaces of the muller. Said channels have their origin at the point at which the beveled edge B, Figure 2, forms an angle with the grinding surface, (this angle is indicated at C, Figure 2,) and extending almost to the outer edge of the grinding surface, (B, Figure 1.) In that type where the channels are present, the non-channelled portion of the grinding surface is an unbroken plane circle surrounding the channelled area, and which may be approximately $\frac{1}{2}$ inch in width. The purpose of these channels is to aid the grinding surface in "taking" the mixture to be ground, thus hastening the action of the appliance. A further aid in feeding the unground material to the grinding surface is provided by having the interior lower edge of the appliance beveled at a suitable angle, this bevel being shown at B, Figure 2. To prevent the discharged, ground product from reentering the muller, the outer right angle formed by the junction of the bottom grinding surface with the exterior wall is made a sharp edge, D, Figure 2.

The muller is used in conjunction with any smooth or matt surface, hard platen or grinding plane, in similar manner to the use of an ordinary muller or spatula.

My invention is a hand operated unit as distinguished from a power operated grinder, and in service my muller is grasped in the hand, and pressure is applied directly to the muller and it is moved in a circular or oscillatory path, in a manner to press and move the lower channelled surface upon the material present between the platen and the lower channeled edge of the muller.

According to my invention, the muller is used primarily for effecting the mixture of pigments with oils, and in the service of the muller the under surface of the unit so acts upon the pigment and oil as to effect an intimate admixture of the specified ingredients without an appreciable grinding action upon the pigment, the latter being pre-ground in a suitable mill in accordance with the usual

procedure in preparing pigments for utilization in the paint art.

In a practical form, the muller is tubular with a cylindrical inner surface and a cylindrical outer surface. The muller is characterized by an under mixing surface the width of which is less than the thickness of the wall of the tubular unit. This reduction in the width of the mixing surface is due to the presence on the inner cylindrical surface of a bevel at the lower edge of the unit. The bevel extends from the inner cylindrical surface to the under mixing surface, the angle of inclination of said bevel affording ample space between the muller and the subjacent platen for insuring an adequate flow of pigment and oil to the under mixing surface.

The muller is constructed to produce an annular wall the thickness of which is usually constant throughout the depth of the muller except for the lower edge portion, at which place the thickness of the wall is decreased by the presence of the bevel provided on the lower inner cylindrical surface.

In the service of my muller, the feed of the pigment and oil is in a direction from the interior of the unit toward the outer side of said unit, and provision is made for excluding the re-entry of the pigment and oil to the interior chamber, a sharp angle defining the juncture of the outer cylindrical surface with the plane surface of the subjacent platen, with the distinct object of wholly precluding the re-entry of the mixed pigment and oil into contact with the under mixing surface of the muller. Briefly, the muller acts efficiently to attain the mixture while the pigment and oil are in contact with the narrow under surface, and once the mixture passes beyond the outer limits of the muller, then the sharp angle at the outer surface acts to exclude the mixture from re-entering below the muller for contact with the channeled mixing surface.

Salient features of my hand operated muller are the bevel at the lower edge on the inner cylindrical surface, and a well defined sharp edge at the lower edge on the outer surface, said sharp outer edge and the bevel on the inner surface bounding and limiting the mixing face at the lower edge, which mixing face is of a width appreciably less than the thickness of the wall of the muller. A further salient feature is the presence in the relatively narrow mixing face of a succession of channels extending tangentially to the inner surface, and in my muller it is required, first, that said channels so direct the pigment and oil in a direction outwardly from the muller, or from the inside toward the outside, and, second, that the channels open through and communicate with the bevel on the inner cylindrical surface and terminate short of the sharp lower outer corner at the outside cylindrical surface.

To attain operativeness, it is required that the muller be provided with the bevel on the inner cylindrical surface at the lower corner thereof whereby provision is made for the flow of materials from the chamber of the muller to the lower mixing surface. For directing the flow of materials in a direction toward the outside of the muller, the channels are positioned in the lower mixing surface tangentially to the inner surface, and to the end that no mixed materials may be permitted to flow beneath, or re-enter below, the mixing face, the outer cylindrical surface of the muller meets with the under mixing face at a sharp angle, the same being a right angle.

The interior of the tubular unit provides a chamber in which is deposited the pigment and oil required to be mixed, and when said muller is in use, the materials flow freely through the bevel and below the mixing face. The muller is efficient to the extent that the mixture is complete once it passes to the outside of the muller, and in my invention the construction excludes the re-entry of the mixed materials below the lower edge of the unit for contact with the mixing face.

The details of the operation of the muller are as follows:

The muller is placed in position upon the grinding platen, with the lower or grinding surface of the muller in contact with the platen. A charge of pigment and vehicle, either previously mixed together, or not mixed (the use of pigment and vehicle is here given for convenience, as representing a well known application of the muller, but the appliance is equally suitable for grinding or mulling pharmaceutical mixtures or any other combination of materials whose intimate blending can be effected by mulling action) is placed inside the muller, and if not previously mixed, the whole is stirred with a rod or other suitable stirring appliance until well blended. The muller is then given a rotary motion or an elliptical or oscillatory movement with the hand, at the same time applying downward pressure upon the muller. The muller immediately leaves in its wake a film of ground product, see Figure 3, which, with the continued rotations or oscillations of the muller, accumulates upon the grinding platen, and by reason of the sharp outer lower angle of the muller does not tend to reenter the muller. The operation is continued until the desired amount of product is obtained, or until the muller is empty, at which point the muller may be recharged with additional material. It will be obvious that no ground material can appear upon the platen outside the muller without having passed between the grinding surface of the muller and the surface of the platen, thus insuring the production of a paste or "paint" completely and uniformly ground.

Although the term "paste" has been con-

veniently applied to the product to exemplify the use of the invention, it should be understood that the invention is equally suitable for the grinding of pigments etc., carrying sufficient vehicle to yield a relatively fluid mixture such as ordinary oil paint.

On account of the relatively small area of the grinding surface of this type of muller, and hence the relatively high pressure per unit of area obtainable with ease in practice as compared with the usual pestle type of muller commonly used, the degree of comminution imparted to the pigments ground with the use of the appliance herein described is much greater in a given time and with less labor than is possible with the existing types of mullers or muller substitutes.

The action of the muller in actual use is illustrated diagrammatically in vertical cross section in Figure 3, A representing the charge of unground material located within the central cavity of the muller; B, Figure 3, represents a portion of this material after having been ground by passing between the lower grinding surface of the muller and the upper surface of the grinding platen, C.

I claim:

1. A hand operated muller comprising a tubular unit the lower edge of which constitutes a mixing face, the interior surface of said unit being cylindrical and provided at the lower edge of said cylindrical surface with a bevel, said bevel being at an angle to the inner cylindrical surface and to the plane of the mixing face.

2. A hand operated muller comprising a tubular unit having at the lower edge a plane mixing face, the inner surface of said unit being cylindrical, said tubular unit being provided in said mixing face with a succession of separate channels extending tangentially to the inner surface, and a bevel at the lower edge of the unit and on the inner cylindrical surface thereof, said separate channels opening through said beveled inner surface of the unit.

3. A hand operated muller embodying a tubular unit provided on a cylindrical inner surface with a bevel and on its under part with a mixing surface, the width of said mixing surface being less than the thickness of the wall of said tubular unit.

4. A hand operated muller embodying a tubular unit the under part of which constitutes a mixing surface, feed channels in said mixing surface, and a bevel on a cylindrical inner surface of said tubular unit, said channels having their origin at the bevel and extending substantially to a line within an outer angle formed by the junction of said mixing surface with the exterior surface of the unit.

5. A hand operated muller embodying a tubular unit the under surface of which constitutes a mixing surface which joins at a

sharp angle with the outer cylindrical surface of the muller, and feed channels in said mixing surface, said feed channels terminating at their outer ends within the sharp angle.

6. A hand operated muller embodying a tubular unit the under part of which constitutes a mixing surface, a bevel on the inner cylindrical surface of said unit, said bevel joining with said mixing surface, and feed channels in said mixing surface, said feed channels extending from said bevel substantially to a line defined by an angle at the juncture of the mixing surface with the outer surface of said tubular unit.

7. A hand operated muller comprising a tubular unit having a cylindrical inner surface and a cylindrical outer surface, a bevel on the inner surface at the lower corner of the unit, said bevel extending from the inner cylindrical surface to the lower edge of the unit and reducing the width of said lower edge to an appreciable extent less than the thickness of the wall of the unit, the outer cylindrical surface and the under surface of said unit being at a right angle, and a succession of feed channels in the under surface, said feed channels being a tangent to the inner cylindrical surface and said feed channels extending from the inner bevel outwardly to a line defined by a right angle formed by the juncture of the lower surface of the unit with the outer cylindrical surface of said unit.
